ROTARY DISPLAY STAND

Robert Palay and Morley Palay, both of 308 S. 3rd St.,
Grand Forks, N. Dak.

Filed Feb. 18, 1958, Ser. No. 715,879

5 Claims. (Cl. 211—1.6)

The present invention relates to, broadly speaking, the problem encountered in most merchandising stores in respect to allocation of space in display windows and also interior space particularly when the space available for such purposes is restricted and of a small area. More particularly, the concept has to do with an apparently acceptable solution of most aspects of the problem and has to do with an unusual and practical rotary display device or stand.

It is realized, of course, that necktie racks, and racks for support of suits and dresses are used in stores and elsewhere to permit turning of the rotatable part by a customer to examine and select merchandise. The present invention is primarily for display purposes and involves the use of a motor driven turntable which supports and rotates a slow turning standard. The standard is supported between the turntable and the ceiling or other horizontal support above it and is provided with one or more collars. The collars are vertically spaced and constructed to accommodately and detachably support novel hangers. The hangers are such in construction that they, in turn, accommodately support varying types of fixtures. The fixtures are detachable and interchangeable in relation to the hangers and allow for systematic and effectual support and display of articles of merchandise such as hats, shirts, shoes and so on.

In carrying out a preferred embodiment of the invention a novel longitudinally extensible standard is utilized. This standard will be set forth in greater detail in the following specification.

Novelty is also predicated, as implied, on unusual perforated collars which are adjustably and detachably mounted on the pole portion of the over-all standard. By providing the collars with a multiplicity of perforations and designing the hangers properly, many hangers may be employed and so arranged that the articles carried by the brackets hung thereon may be arranged and displayed to the advantage of all concerned.

Another but more general objective is to structurally, functionally and otherwise improve upon similarly constructed and performing so-called store furniture having to do with racks, stands and the like and, in doing so, to provide an adaptation which, it is submitted, will comply with the wishes of manufacturers and needs of merchandisers and customers alike.

Other objects, features and advantages will become more readily apparent from the following description and the accompanying drawings.

In the drawings wherein like numerals are employed to designate like parts throughout the same:

Fig. 1 is a perspective view showing the novel and improved rotary display stand and how it is constructed and preferably used.

2

Fig. 2 is an enlarged view in section and elevation taken approximately on the plane of the line 2—2 of Fig. 1, looking in the direction of the arrows.

Fig. 3 is a view on an enlarged scale showing the motor driven turntable.

Fig. 4 is an enlarged perspective detailing one of the hub-like hanger supporting collars.

Fig. 5 is a top plan view of the construction shown in Fig. 4 with the hanger removed.

Fig. 6 is an enlarged section on the vertical line 6—6 of Fig. 4.

Fig. 7 is a view showing in perspective one of the J-shaped hangers and a hat racking fixture.

Fig. 8 is a fragmentary view in section and elevation showing a slight modification of the lower end construction of the standard.

Fig. 9 is a view of a fragmentary nature in section and elevation showing a slight modification wherein shelf means, an optional addition, is supported atop the perforated collar.

With reference now to the views of the drawings with the aid of reference characters, the standard in a unitary sense is denoted by the numeral 10 in Fig. 1. It is of a composite construction and is vertically extensible and contractible so that it may be fitted properly between the floor or other support A at the bottom and ceiling or equivalent surface B at the top. A preferred embodiment of the standard comprises a suitable length wooden or equivalent pole 12. The lower end of this pole is fitted into a simple rubber or equivalent friction driving cap or base 14. The upper end, as seen in Fig. 2, has a reduced shouldered neck 16 to accommodate a telescoping part which is here referred to as either a plunger or jack 18. This part 18 comprises a lower smaller sleeve 20 fitting over the neck 16 and fastened thereto at 22. This smaller sleeve telescopes into the lower portion of the outer and larger sleeve 24. There is a coil spring 26 nested in the sleeve 24 and resting at its lower end against the sleeve 20 and at its upper end against a plug 28 which is fitted and secured at 30 in the upper end of the sleeve 24. The plug has a central upstanding journal 32 rotating in a suitably constructed ball bearing fitting or race 34 which is in turn fitted into the cup portion 36 of a rubber or equivalent end-thrust cap 38. The cap 38 bears frictionally against the ceiling B. As seen in Fig. 3, the base 14 rests atop a metal or an equivalent disk 40 providing a turntable and having a driven socket 42 on its bottom to accommodately receive the drive shaft 44 extending from the gear box 46 the gearing of which (not shown) is suitably driven by an off-side motor 48 having a current conductor 50 connected thereto. Thus by way of the motor and gearing and shaft and socket means the turntable is set into rotation and it, in turn, rotates the complete standard 10 as a unit. The upper end of the standard rotates freely in the bearing means shown in Fig. 2.

Any number of racking collars may be provided and removably fitted on the standard. One such collar denoted by the numeral 52 is shown in Figs. 4 and 5 and comprises a sheet metal endless band 54 having a multiplicity of holes or apertures 56 provided therein for selective use. A spider is employed to attach the collar to the pole and the spider comprises a radially circumferentially spaced spider arms 58 (Fig. 5) connected at 65 their outer ends to the collar and at their inner ends to a split band or collar 60 which immediately embraces the pole, the split end portions 62 thereof being bolted

together at 64. These hub-like collars serve to accommodate support the unique J-shaped hanger units each of which is denoted by the numeral 66 (see Fig. 7).

The hanger is made from rod stock of appropriate strength and gauge and the linearly straight shank portion 68 has a U-shaped head or yoke at the top. The arms 70 terminate in laterally off-set fingers 72 which are fittingly adapted to be detachably and selectively mounted in the holes 56 in the manner shown in Fig. 6. The curvate lower end portion 74 provides the hook-like terminal of the "J" and terminates in a screw-threaded end 76 which is adapted to accommodate an internally screw-threaded socket. For example, the stated socket is provided on all the interchangeable and selectively usable fixtures which are employed to support the hats, shirts and shoes illustrated in Fig. 1. One of these fixtures as seen in Fig. 7 is that for supporting a hat and it is denoted by the numeral 78 and it has the desired socket 80 which fits on the screw-threaded end 76. It seems unnecessary to dwell at length on the other fixtures other than to say that, for example, the shirt fixture seen in Fig. 1 is denoted by the numeral 82 and has a socket 84 like the socket 80. This fixture is a sort of openwork or fabricated plate having a bent up hook-like ledge 86 at the bottom for shirt seating, backing and supporting purposes. The fixtures which are employed to support shoes are different in construction and are denoted at 88 in Fig. 1. Each fixture 88 has a socket 90 like the sockets 84 and 80. Thus the unique attachable and detachable J-shaped hangers 66 serve to accommodate a variety of brackets or fixtures.

The purpose of Fig. 8 is to show that the pole 12 may also be in the form of an aluminum or equivalent metal tube which is denoted by the numeral 92 and which serves to accommodate an adjusting tubular sleeve 94 held in place by screw fasteners 96 fastening into holes 98 provided therefor.

With further reference to the inverted U-shaped spiders or brackets 58 it will be noticed that these have their median portions provided with bolt holes 59 (Fig. 5). These bolt holes serve advantageously to accommodate bolts, screws or similar fastenings 61, which, as shown in Fig. 9, are suitably employed to support and hold in place semi-circular half-sections 53 which cooperate in providing a suitable horizontal circular or equivalent miscellaneous article-supporting shelf. It follows that it is within the purview of this invention to aptly utilize the collars 52 and brackets or spiders 58 not only in the association and arrangement seen best in Fig. 4, but also according to the optional arrangement depicted in Fig. 9, which makes possible the use of an often-desired shelf. The bight or intermediate portions of the spiders or brackets are preferably flush with the upper edge of the collar to insure ready and reliable mounting of the shelf sections in the manner illustrated.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A rotary display stand and rack for use in department stores and elsewhere for window as well as interior use comprising a motor driven turntable adapted to rest on a lower support surface, a longitudinally extensible and contractible standard having a friction driven base cap resting atop the central portion of said turntable, a spring-biased plunger constituting the upper end portion of said standard and having a bearing equipped rubber cap adapted to rest against a ceiling above said lower support surface, a perforated collar detachably

and adjustably mounted on said standard, at least one hanger fixture, said fixture being J-shaped and formed from a rod and embodying a vertical linearly straight shank provided at its upper end with a U-shaped attaching head including arms and offset attaching and retaining fingers, said fingers being adapted to be selectively and removably mounted in the perforations provided therefor in said collar, the lower end of said rod being curved and terminating in a screw-threaded portion to accommodate a socket member on an attachable and detachable article accommodating and supporting fixture.

2. For use in cooperation with a supporting collar on a standard, a hanger of J-shaped form having a linearly straight rod portion forming a shank and provided at an upper end with a U-shaped yoke, and yoke including arms and said arms having offset hook-like attaching fingers, the lower end portion of said rod being curvate and screw-threaded.

3. For use on and in association with a turntable rotatably supported member constituting a standard, an inner collar clamped on said standard, an outer collar encircling said inner collar, inverted U-shaped reinforcing spiders arranged in the space between said collars and having inner end portions attached to the outer periphery

25 of the inner collar and outer end depending portions attached to the inner periphery of the outer collar and having bight portions flush with the upper edge of the outer collar, said bight portion having a bolt hole, and a sectional shelf having sections resting atop the outer collar and bight portions of the spiders and attached to the spiders by way of fasteners cooperating with the bolt holes.

4. A rotary display stand comprising, in combination, a motor driven turntable adapted to be supported on a floor or an equivalent foundation, a longitudinally extensible and retractable standard adapted to be located vertically when in use and having a main pole portion provided at its lower end with a rubber cap providing a base which rests removably atop the turntable, and telescoping spring-biased means carried by the upper end of the pole and adapted to bear against a ceiling or other support surface above said floor, said means comprising a first tube fixed to the upper end portion

40 of the pole and fitting telescoped into a second complementary tube, the second tube provided and closed at its upper end with a plug terminating in an upstanding axial journal, a coil spring arranged in the second tube and bearing at one end against the plug and at the opposite end against the upper end of said first tube, a cup-like end thrust cap adapted to rest against said ceiling and provided with an anti-friction bearing, said journal being mounted for rotation in said bearing, a collar encircling and adjustably mounted on said pole and provided with a multiplicity of selectively usable holes, and a readily attachable and detachable hanger bracket comprising a J-shaped member having a shank provided at its upper end with a U-shaped head formed with offset attaching and retaining fingers adapted to be separably

45 connected to said collar by way of said holes and also having a curved lower end portion terminating in a screw-threaded end, and a readily attachable and detachable article accommodating fixture having a socket member screwed and supported on said screw-threaded end.

5. For use on and in association with a supporting standard, inner and outer concentric radially spaced collars, said inner collar providing a hub and being adapted to be detachably and adjustably mounted on a supporting standard, equidistant circumferentially spaced spider arms interposed between and securing said collars together in cooperative relationship, said outer collar being relatively wide and provided with selectively usable perforations, the bight portions of said spiders being flush with the upper edge of the outer collar and having bolt holes

50

70

75

and being adapted to seat and support an optionally usable shelf made up of sections adapted to rest atop the bight portions and adapted to be bolted thereto, and at least one substantially J-shaped hanger having a curvate lower end portion terminating in an end portion which is adapted to support a readily applicable and removable article supporting fixture and having a shank portion provided with at least one finger separably connectible to the outer collar by way of one of the perforations in said outer collar.
